(57) **CLAIM**

The ornamental design for a free weight covering, as shown and described.

DESCRIPTION

FIG. 1 is a perspective view of a free weight covering showing my new design.

FIG. 2 is an alternate perspective view of the free weight covering shown in FIG. 1.

FIG. 3 is a front view of the free weight covering shown in FIG. 1.

FIG. 4 is a back view of the free weight covering shown in FIG. 1.

FIG. 5 is a left side view of the free weight covering shown in FIG. 1, the right side view being a mirror image thereof.

FIG. 6 is a top view of the free weight covering shown in FIG. 1, the bottom view being a mirror image thereof.

FIG. 7 is a cross-sectional view of the free weight covering taken along line 7 in FIG. 6.

FIG. 8 is an alternate perspective view of the free weight covering shown in an environment of use.

FIG. 9 is an alternate front view of the free weight covering shown in an environment of use; and,

FIG. 10 is an alternate perspective view of the free weight covering shown in a second environment of use.

The broken lines in FIG. 6 show the section arrows for the cross-sectional view and form no part of the claimed design. The broken lines in FIGS. 8-10 show environment and form no part of the claimed design.

The free weight covering disclosed herein is of a flexible material that takes on the shape of the weight.

1 Claim, 10 Drawing Sheets
